UNITED STATES PATENT OFFICE.

NOAH COATE, OF GREENVILLE, OHIO.

APPARATUS FOR MANUFACTURING ICE.

Application filed April 17, 1922. Serial No. 553,336.

To all whom it may concern:

Be it known that I, NOAH COATE, a citizen of the United States, residing at Greenville, in the county of Darke and State of Ohio, have invented certain new and useful Improvements in Apparatus for Manufacturing Ice, of which the following is a specification.

This invention relates to a novel method 10 of and apparatus for manufacturing ice and has as its general object to provide means whereby ice may be manufactured in blocks at a minimum cost wherever climatic conditions are suitable.

15 The present invention contemplates the production of ice in blocks where the atmospheric temperature is below freezing, the general proposition being to expose a number of cans of water to the freezing temperature and thus produce blocks of ice, and one of the objects of the present invention is to provide means whereby to effect a solidification of the water in a manner to allow for free upward expansion in the cans 20 as the ice is formed and thus prevent bursting of the cans or their subjection to stresses which would be imposed if no such means were provided.

Another object of the invention is to devise an apparatus for the carrying out of the invention in the nature of a building structure having its several parts so arranged as to provide for the most expeditious production of ice.

35 Another object of the invention is to provide within the structure means whereby the ice formed in any one of the several cans may be readily loosened to permit of its being discharged in block form from the can 40 and without the necessity of striking blows upon the can.

In the accompanying drawings:

Figure 1 is a view in elevation of the building structure constituting the apparatus for carrying out the method of the invention;

Figure 2 is a vertical transverse sectional view through the front part of the structure;

50 Figure 3 is a vertical longitudinal sectional view through the structure;

Figure 4 is a horizontal sectional view taken substantially on the line 4—4 of Figure 2;

Figure 5 is a detail transverse sectional view through one of the cans;

Figure 6 is a detail vertical sectional view taken substantially on the line 6—6 of Fig. 2 looking in the direction indicated by the arrows;

Figure 7 is a perspective view illustrating a tilttable rack;

Figure 8 is a similar view illustrating a housing in which the rack shown in Figure 7 is mounted.

The apparatus by which the method of the invention is carried out is in the nature of a building structure indicated in general by the numeral 1 and comprising side walls 2, a rear end wall 3, a front wall 4, and a roof 5. The upper portion of the structure is preferably closed on all sides, a door 6 being provided however at some convenient point in one of the walls 2, 3 or 4, whereby entrance may be gained to the upper portion of the structure. The lower portion of the structure is open at its ends and also if desired at its sides by providing doorways 7 in the corresponding walls and which doorways may be closed by doors 8 slidably or otherwise mounted.

The upper and lower portions of the interior of the structure are separated or divided by the assemblage of water cans in which the water is to be frozen, and these 85 cans are indicated in general by the numeral 9 and each is preferably of the rectangular form illustrated in the drawings and comprises side walls 10, end walls 11, and a bottom 12, each can being open at its top. The cans may be of sheet metal, or otherwise formed, and there is arranged and secured upon the exterior of each can a supporting flange 14 which may be in the nature of an angle iron bar shaped to rectangular frame-like form and surrounding the open top of the can. The projecting wings of the supporting flanges 14 are designed to rest upon the upper edges of stringers 15 built within the structure 1, the cans being in this manner suspended between the stringers so that all except their open tops will be exposed to the atmosphere within the lower or cold zone of the structure. As the cans are disposed close together and side by side and the assemblage extends over substantially

100 the entire area of the interior of the structure 1, the assemblage will as stated separate 105

or divide the interior of the structure into upper and lower sections or zones. Therefore when the doors 8 are opened and air is permitted to circulate freely through the 5 structure beneath the assemblage of cans, this portion of the interior of the structure will constitute a cold or refrigerating zone. However the upper portion of the interior of the structure constitutes a zone in which 10 other temperature conditions prevail as will now be explained.

The stringers 15 are so arranged as to provide an opening 16 located at a suitable point within the structure preferably near 15 the wall 4 thereof. Arranged within the opening 16 is a housing 17 open at its top and bottom and at its side which is presented toward the rear wall 3 of the structure, the said housing comprising side walls 20 18 and a rear wall 19. The purpose of this housing will be presently explained. Arranged within the open bottom of the housing is a grating or register 20 through which heated air is to be delivered from a pipeless 25 furnace indicated by the numeral 21, this furnace being located within the cold or refrigerating zone of the structure where it may be conveniently attended. For a purpose to be presently explained a tank 22 is 30 arranged between two of the stringers 15 adjacent the furnace 21, and pipes 23 and 24 lead from a water coil or water space within the furnace 21 and communicate with the tank 22, the pipe 23 being designed 35 to conduct water from the water space of the furnace to the upper portion of the tank 22, and the pipe 24 being designed to conduct water from the bottom of said tank 22 to the said water space of the furnace. In this manner water within the tank 22 is maintained at a more or less elevated 40 temperature.

The numeral 25 indicates in general a 45 rack or supporting frame structure which is mounted within the housing 17 and comprises sides 26, a bottom 27, a cleat 28 which extends across the front of the structure at the forward edge of the bottom 27, a cleat 29 which extends in a front to rear direction 50 along the upper side of the bottom 27 between the sides 26, cross pieces 30 which extend between the said sides 26 near their upper ends, and a division piece 31 which extends between the cross pieces 30. This 55 frame is provided upon its sides 26 with trunnions 32 which are mounted in suitable bearings 33 upon the inner faces of the sides 18 of the housing 17, and in this manner the said structure 25 is supported for tilting movement so that it may occupy the upright position shown in Fig. 6 of the drawings, in full lines, or may be tilted to assume a more or less horizontal position as illustrated in dotted lines in said figure. 60 The numeral 34 indicates a chute which

leads downwardly from the open front of the housing 17, as best shown in Figs. 3 and 6 of the drawings, and is adapted to discharge into any convenient storage space either within or exterior to the structure, 70 the receiving end of the chute being located in such position that when the frame structure 25 is tilted to the dotted line position shown in Fig. 6, the open top of the frame structure will be disposed directly above the 75 said end of the chute. For a purpose to be presently explained a gutter 36 is formed or provided in the grating 20 about the reticulated area of the grating, as best shown in Fig. 6. 80

In carrying out the method, the cans 9 are filled with water as is also the tank 22, the doors 8 are opened to permit the free circulation of air through the cold or refrigerating zone of the structure, and a moderate 85 fire is built in the furnace 21. The heated air currents delivered from the furnace 21 will pass up through the register or grating 20 and circulate in the upper or temperate zone of the structure and by their presence 90 will retard the freezing of the water in the cans near the surface. However, the lower portions of the cans are exposed to the cold atmospheric currents in the cold or refrigerating zone of the structure, and in a short 95 space of time the water will congeal and freeze in the cans, this change in form taking place gradually in an upward direction rather than from the surface downward as is the case where a container of water is 100 exposed on all sides to the atmosphere at a freezing temperature. When the contents of the cans have become completely frozen, the formed blocks of ice may be discharged therefrom in the following manner. The 105 frame structure 25 is adapted to receive and support two of the cans 9, as best shown in Figs. 2 and 6 of the drawings, and the cans are placed within the said structure and while supported thereby will be exposed 110 to the heated air currents rising through the register or grating 20. This will serve to loosen the cakes of ice formed within the cans, and if desired, during this operation, a removable lid 37 may be applied to the 115 top of each can so as to equalize the temperature. After the blocks of ice have been loosened in the manner stated, the lids 37 are removed, and the structure 25 is then tilted upon the trunnions 32 from the full 120 line position shown in Fig. 6 to substantially the dotted line position shown in said figure whereupon the blocks of ice will be discharged from the cans into the upper end of the chute 24 and will slide by gravity 125 down this chute to the delivery end thereof.

When it is found expedient or desirable, any one of the cans may be removed from its position where it is supported by the stringers 15 and may be temporarily immersed in the 130

water in the tank 22 so as to effect a loosening of the block of ice formed in the can whereupon the block may be readily dislodged.

5. Preferably a number of boards 38 are disposed within the structure promiscuously upon the top of the cans supported by the stringers and may be moved about from place to place and thus employed as a surface upon which an attendant may walk in replenishing the cans or attending to the discharge of the cakes of ice formed therein.

10. The gutter 36 constitutes a means for collecting any water which may be discharged from the cans as result of the partial thawing of the ice block while the cans are supported within the structure 25.

Having thus described the invention what is claimed as new is:

20. 1. An apparatus for the manufacture of ice comprising a structure having an enclosed upper chamber and a lower refrigerating chamber which latter is adapted to be open to the atmosphere, means for supporting a water container within the refrigerating chamber of the structure with its top presented within the upper chamber, and means for maintaining a temperature above freezing within said upper chamber.
25. 2. In apparatus for the manufacture of ice, a structure having an enclosed upper chamber and a lower chamber which latter is open to the atmosphere, a container supported within the structure with its major lower portion situated within the said lower chamber and having an open top presented within the upper chamber, and means for supplying heated air currents to the said upper chamber.
30. 3. In apparatus for the manufacture of ice, a structure having an enclosed upper chamber and a lower chamber which latter is open to the atmosphere, a container supported within the structure with its major lower portion situated within the said lower chamber and having an open top presented within the upper chamber, and means for supplying heated air currents to the said upper chamber.
35. 4. In apparatus for the manufacture of ice, a structure having an enclosed upper chamber and a lower chamber which latter is open to the atmosphere, a container supported within the structure with its major lower portion situated within the said lower chamber and having an open top presented within the upper chamber, and means for supplying heated air currents to the said upper chamber.
40. 5. In apparatus for the manufacture of ice, a structure having an enclosed upper chamber and a lower chamber which latter is open to the atmosphere, a container sup-

ported within the structure with its major lower portion situated within the said lower chamber and having an open top presented within the upper chamber, and means for supplying heated air currents to the said upper chamber, said means comprising a heating furnace arranged within the said lower chamber and having its hot air outlet positioned to discharge into the upper chamber.

4. In apparatus for the manufacture of ice, a structure having an enclosed upper chamber and a lower chamber which latter is open to the atmosphere, a container supported within the structure with its major lower portion situated within the said lower chamber and having an open top presented within the upper chamber, heating means for supplying heated air currents to the said upper chamber, a water tank within the structure, and means for supplying heated water from the heating means to the said tank, the first mentioned container being displacedly supported whereby it may be removed from its supporting means and immersed in said tank.

5. In apparatus for the manufacture of ice, a structure having an enclosed upper chamber and a lower chamber which latter is open to the atmosphere, a container supported within the structure with its major lower portion situated within the said lower chamber and having an open top presented within the upper chamber, means for supplying heated air currents to the said upper chamber, said means comprising a heating furnace arranged within the said lower chamber and having its hot air outlet positioned to discharge into the upper chamber, and a tiltable supporting means for said container located above the heating furnace.

In testimony whereof I affix my signature. NOAH COATE.
